NO. 12,166

UNITED STATES PATENT OFFICE.

OLIVER B. KEELEY, OF SPRING CITY, AND JAMES M. ATCHISON, OF PHILADELPHIA, PENNSYLVANIA, ASSIGNORS TO SAID KEELEY.

DESIGN FOR A COOKING-STOVE.

SPECIFICATION forming part of Design No. 12,166, dated February 15, 1881.

Application filed January 18, 1881. Term of patent 7 years.

To all whom it may concern:

Be it known that we, OLIVER B. KEELEY, a citizen of the United States, residing in Spring City, Chester County, Pennsylvania, and 5 JAMES M. ATCHISON, a citizen of the United States, residing in Philadelphia, Pennsylvania, have invented a new and original Design for a Cooking-Stove, of which the following is a specification.

10 Our design is fully shown in the accompanying drawing, which represents a perspective view of the stove.

15 The main oven-door is L-shaped and has an ornamental border, *a*, inclosing the central raised portion *b*, the edge *d* of which has ornaments *e*. The portion *b* of the door has line-work corner-ornaments, *f*, and a central panel, *g*. This panel is oblong and eight-sided, has beveled edges with ornaments, as shown, and 20 has a roughened face with monogram.

25 The door-handle *h* has a raised boss, *i*, and the face of the handle has a central ornament in the shape of a crown, and other ornaments on each side of the same.

30 The end fire-door corresponds in ornamentation with the oven-door, but is of rectangular form.

35 The front fire-doors have each two mica panels. The feet *m* are partly flat and partly curved, the flat portions having line-work ornaments *n*, and the curved portions having line-work ornaments *s*.

The top, hearth-plate, and base of the stove have beveled and polished edges *w*.

We claim—

1. The design for the oven-door, said design comprising the ornamental border *a*, raised central portion, *b*, ornaments *e f*, and central panel, *g*, as shown and described. 35

2. The design for the oblong eight-sided panel *g*, having beveled and ornamented edges and monogram face, as shown and described. 40

3. The design for the handle *h*, having a raised boss, *i*, and face with central and side ornaments, as shown and described. 45

4. The design for the feet *m*, partly flat and partly curved, with ornament *n* on flat face and ornament *s* on curved face, as shown and described.

5. The design for the complete stove, comprising the beveled top, hearth, and baseplates, oven-door, end fire-door, front fire-doors, and feet, all ornamented as shown and described. 50

In testimony whereof we have signed our names to this specification in the presence of 55 two subscribing witnesses.

OLIVER B. KEELEY.
JAMES M. ATCHISON.
